FIG. 3

FIG. 2

FIG. 1

FIG. 5

FIG. 4

FIGURE 1 is a front elevational view of a weighing scale pointer, showing my new design.

FIGURE 2 is a side elevational view thereof, the undisclosed side being substantially the same in appearance.

FIGURE 3 is a top plan view.

FIGURE 4 is a rear elevational view of the weighing scale pointer of FIGURE 1.

FIGURE 5 is a section on line 5—5 of FIGURE 4.

The fragmentary showing of the scale dial in broken lines is for illustrative purposes only.

I claim:

The ornamental design for a weighing scale pointer, substantially as shown and described.
